UNITED STATES PATENT OFFICE.

CARL FRIEDRICH SIMON, OF STOLLMERG, GERMANY, ASSIGNOR TO CHEMISCHE FABRIK RHENANIA, OF AACHEN, GERMANY.

PUMP FOR RAISING LIQUIDS BY COMPRESSED AIR.

SPECIFICATION forming part of Letters Patent No. 723,744, dated March 24, 1903.

Application filed July 28, 1902. Serial No. 117,400. (No model.)

To all whom it may concern:

Be it known that I, CARL FRIEDRICH SIMON, a citizen of Germany, residing at Stollberg, Germany, have invented a certain new and useful Pump for Raising Liquids by Compressed Air, (for which I have made application for a patent in Germany, dated May 30, 1902,) of which the following is a specification.

This invention relates to a pump for raising liquids by compressed air, as will be described with reference to the accompanying drawings, in which—

Figure 1 shows the distributing-valve mechanism in vertical section. Fig. 2 is a transverse section on line A B, Fig. 1; and Fig. 3 is an elevation of the containers with its liquid and compressed-air connections broken away.

The container *a* being empty, liquid flows thereinto through the pipe *b*, which has a check-valve *c*. The air thus displaced escapes through the pipe *d*, past the valve *e*, and through the pipe *f*. At the same time air is passing from the main compressed-air pipe *h* through the valve-casing *h'* and the pipe *g*, having a regulating-valve *g'*, into the air-chamber *i*, where there is thus a pressure slowly created. Through the pipe *k* this pressure is communicated to the space *l* behind the piston *m*.

While the container *a* is being filled container *n* is being emptied by the action of compressed air, and as soon as the level of the liquid in it is below the lower end of pipe *o* the compressed air in the container escapes up this pipe and the pressure in *n* falls, thus removing the pressure on the one side of valve *p* and piston *m*, which sides are in communication with container *n*, through pipes *q* and *r*, respectively. The pressure in air-chamber *s* also falls, for the latter is in communication with space *t*, through pipe *u*, and the pipe *y*, provided with regulating-valve *y'*, is closed by the valve *h'*. When this counter-pressure on the piston *m* has fallen to a certain value, the pressure in the space *l* suffices to move the piston, thus opening the valve *p* and closing the valve *e*. The same movement of the piston closes the pipe *r*,

which conveys compressed air to the container *n* and opens the pipe *w*, which fulfills the same function for container *a*. Thus the latter is put under pressure, while the pressure in container *n* falls to that of the atmosphere, and the check-valve *z* opens, admitting fresh liquid. In moving the piston *m* strikes the tappet *h'* and moves the valve *h'* to close the pipe *g* and open the pipe *y*. The air vessel *s* is now in communication with the compressed-air supply, and the pressure in it gradually rises. This pressure is communicated to the space *t* through pipe *u*, so that this end of the piston *m* is slowly put under pressure, the pipe *r* being closed. The pipe *w* being now open and the pipe *g* closed, the air-chamber *i* is in communication through space *l* with the container *a*. As soon as container *a* is empty and the compressed air can escape up the pipe *o* the piston *m* is moved back and the cycle is repeated.

To avoid loss of air, the duration of filling should be somewhat shorter than that of emptying the container.

Having thus described the nature of this invention and the best means I know of carrying the same into practical effect, I claim—

1. A pump for raising liquids by compressed air comprising two liquid-containers provided with liquid-supply and delivery and air-pressure pipes, two air-pressure reservoirs connected to a compressed-air supply, a cylinder and piston worked from the compressed-air supply, and valves operated by the said piston and adapted to alternately connect one air-reservoir with a liquid-container while disconnecting the other air-reservoir from the other liquid-container, substantially as described.

2. In an apparatus for raising liquid by compressed air, a distributing-valve, a pair of compressed-air chambers communicating with receptacles containing the liquid to be raised and with a compressed-air supply, means for directing a pressure of air against said valve to move it during the emptying of one of the receptacles containing the liquid, thereby closing the communication between one of said chambers and one of the recepta-

cles and to establish communication between the other of said receptacles and the other of said chambers, and an auxiliary valve operated by the movement of said distributing valve for alternately connecting said chambers with the compressed-air supply.

In testimony whereof I have hereunto set

my hand in presence of two subscribing witnesses.

CARL FRIEDRICH SIMON.
